SHAVING IMPLEMENT

Nicholas Testi, Boston, Mass., assignor to Gillette
 Safety Razor Company, Boston, Mass., a corporation of Delaware

Application March 10, 1938, Serial No. 195,125

13 Claims. (Cl. 30—43)

This invention relates to implements designed for shaving without the use of lather and to that end employing cooperating shearing members. The general objects of the invention are to improve implements of this class in respect to economy of construction and facility in replacement of parts as well as to improve the efficiency and closeness of their function in shaving.

An important feature of my invention consists in a shearing member or blade of thin sheet steel, for example, such steel as is commonly used for safety razor blades or other thin resilient strip stock which may be obtained commercially in very accurate dimensions and of a thickness of .004" or thereabouts. I have found that a stationary shearing member may be fashioned from such strip stock by transversely curving or bowing the stock and thereby rendering it sufficiently stiff in cross-section to maintain its shape in use. The employment of such stock insures a product of uniform character and obviates the necessity of expensive grinding operations which would otherwise be necessary in order to secure anywhere near a similar degree of uniformity in this important element of the implement. A shearing member of this character may be constructed at very low cost and so may be replaced at little expense at the first indication of dullness. Thus the user is insured of a shaving implement operating always with a high degree of efficiency.

Another important feature of my invention consists in an adjustable blade-flexing member operating to flex a stationary shearing member independently of the movable cutter and having no motion in the operation of the implement developing objectionable friction, that is to say, having an adjusting movement but no longitudinal movement with reference to the blade. This construction permits adjusting the flexible shearing blade to any desired degree of curvature without in any way affecting the pressure of contact between it and the movable cutter. In general the pick-up efficiency of the shearing blade is improved by increasing its transverse curvature and it is, of course, desirable to maintain constant and moderate pressure between the curved blade and the cutter under all conditions of curvature. In one important aspect therefore my invention consists in a shaving implement having a flexible shearing blade retained at its edges in a holder, in combination with a normally stationary but adjustable blade-flexing member and a movable cutter maintained in engagement with the flexed blade. Preferably and as herein shown separate yielding means are provided for maintaining the cutter in shearing engagement with the flexed blade.

While the present invention contemplates flexing the stationary shearing blade to any de-

sired degree of transverse curvature it is desirable from the standpoint of commercial manufacture to provide the implement with blade-flexing means by which the shearing blades in a quantity of implements may be quickly and accurately flexed to the same degree in order that the contour of the cutters may be given a corresponding curvature. As herein shown headed screws are provided for moving the blade-flexing member and these are so designed that when screwed into the limit of their movement the desired predetermined curvature will be imparted to the flexible shearing blade, that being the curvature of the contour of the cutter supplied in the implement.

The shape and location of the blade-flexing member is of secondary importance. It may be arranged to compress the blade edgewise or to engage the flat face of a blade held at its longitudinal edges and in the accompanying drawings blade-flexing members of both types are illustrated. One satisfactory form of blade-flexing member comprises a bar which is U-shaped in cross-section so that it presents spaced walls for engaging the face of the flexible blade and where this construction is employed the cutter may be mounted for movement between the walls of the blade-flexing member. In this construction, or in any construction where the blade-flexing member engages the face of the flexible blade, I have found it advisable to slot the walls of the flexing member to provide transverse hair passages in alignment with the apertures of the blade which provide the shearing teeth therein so that hairs may pass freely in a transverse direction into the shearing zone of the implement.

These and other features of the invention will be best understood and appreciated from the following description of preferred embodiments thereof, selected for purposes of illustration and shown in the accompanying drawings, in which—

Fig. 1 is a view of the implement in end elevation on an enlarged scale, a portion of the casing being shown as broken away;

Fig. 2 is a view in longitudinal section corresponding to Fig. 1;

Fig. 3 is a sectional view of the head on a still larger scale on the line 3—3 of Fig. 2;

Fig. 4 is a fragmentary plan view on the scale of Fig. 3;

Fig. 5 is a fragmentary view in cross-section of the head illustrating a modified construction;

Fig. 6 is a corresponding fragmentary plan view;

Fig. 7 is a fragmentary sectional view showing the blade-flexing member in a different position from that shown in Fig. 5;

Figs. 8 and 9 are views in perspective of blades of alternative design;

Fig. 10 is a view of an alternative form of implement shown in section on the line 10—10 of Fig. 11;

Fig. 11 is a corresponding view in longitudinal section;

Fig. 12 is a fragmentary view in perspective of a blade of still another alternative form;

Fig. 13 is a view corresponding to Fig. 10 but showing the head removed;

Fig. 14 is a view in side elevation of the blade 10 flexing member and associated parts;

Fig. 15 is a view in end elevation of a head of alternative construction;

Fig. 16 is a corresponding view showing the blade clamped in flexed position in the head of 15 Fig. 15; and

Fig. 17 is a fragmentary view in elevation, partly in section corresponding to Fig. 16.

The implement shown in Figs. 1-4 includes in its structure an elongated handle 10 of "Bakelite" 20 or other mouldable material which is shaped to serve also as the housing of an operating motor for the implement. At its upper end, the handle is provided with a socket formed by spaced flanges for the reception of the metallic head of the implement. For retaining this in place a clamping screw 11 is provided in one of the side flanges of the handle.

The head 12 is an elongated steel member having a wide, downwardly extending, centrally disposed rib 13 arranged to fit into the socket of the handle and to be engaged by the clamping screw 11. The head is provided with upstanding longitudinal side flanges at its edges defining a wide open space in the head and in the inner walls of the side flanges are formed deep transverse channels 14 extending from one end to the other of the flanges. The channels 14 are disposed opposite to each other at the same level and are arranged to receive the opposite edges of a thin 40 flexible blade 15.

The blade may be slipped endwise into the channels 14 while in flat condition and is subsequently bowed upwardly as will be presently explained. The blade herein shown for purposes of illustration is provided with a series of apertures in the shape of transverse slots 16 forming shearing teeth and also has a centrally disposed notch 17 in each end.

The head 12 is provided with a central longitudinal channel of rectangular cross-section and in this is mounted an elongated blade-flexing member 18 which is U-shaped in cross section and initially located with the top of its side walls slightly below the plane of the blade 15 when the latter is positioned with its edges in the channels 14. The blade flexing member 18 is provided at both ends of its walls with upstanding end lugs 19 and these are arranged to project in spaced relation into the end notches 17 of the blade when the latter is flexed and so anchor it positively against longitudinal displacement in the implement.

The blade flexing member 18 is supported upon the upper ends of a pair of adjusting screws 20 which are threaded into the rib 13 of the head and provided with pilot extensions passing upwardly into holes provided for that purpose in the bottom of the blade flexing member 18 and so holding that member against longitudinal movement in the head. After the blade 15 has been properly positioned in the head the screws 20 are turned inwardly forcing the blade flexing member 18 ahead of them into engagement with the lower face of the blade 15. The screws 20 are

turned inwardly until the blade is flexed transversely into an upwardly bowed condition as shown in Fig. 1 and by dot-and-dash lines in Fig. 3. The degree of curvature imparted to the blade may be adjusted to a nicety by manipulation of the screws 20, although it is limited by the position to which the ends of the screws may be elevated when their heads engage the bottom of the rib 13. In the upward movement of the member 18 its side walls engage the blade along parallel lines spaced inwardly from the sides of the head and located in the open space between the sides thereof.

A cutter comprising an elongated bar 21 is mounted for reciprocation between the side flanges of the blade flexing member 18. The cutter is provided in its upper edge with transverse slots forming shearing teeth 22 and is arranged to be yieldingly pressed at all times against the lower face of the flexed blade 15. To this end the lower wall of the blade flexing member 18 and the rib 13 of the head are provided with a pair of concentric bores in which are disposed vertical pins 23, each having a collar beneath which is engaged the upper end of a compression spring 24. The pins 23 are provided with heads at their lower ends which are received in recesses formed in the handle 10. The pins 23 pass through a retaining plate 25 fastened to the handle 10 and the compression springs 24 are engaged between the upper face of this plate and the collars upon the pins. It will thus be seen that the pins are urged upwardly at all times and serve to hold the cutter 21 yieldingly against the blade 15, being rounded at their upper ends to permit longitudinal vibration of the cutter bar without undue friction.

The cutter is reciprocated by a motor disposed within the handle or housing 10. In Fig. 2 a portion of the rotor 26 is shown and from this projects upwardly a shaft 27 having a driving eccentric 28 upon its upper end. The eccentric 28 is received within a recess in the bottom of the cutter 21. The intervening portions of the blade-flexing member 18, of the rib 13 and of the handle 10 are bored to provide for the passage of the shaft 27 with suitable clearance.

It will be understood that while the blade-flexing member 18 and cutter occupy their lowered position as shown in Fig. 3, the blade 15 is free to be moved endwise out of the channels 14 in the head for purposes of cleaning or replacement. When the blade is positioned in the head the blade-flexing member 18 may be elevated to impart the desired degree of curvature to the blade. In this flexing movement the edges of the blade are drawn somewhat together but the channels 14 are of sufficient depth to preclude the danger of disengagement. The height to which the blade flexing member can be lifted is limited by the length of the screws 20. In Figs. 1 and 2 it will be noted that the screws 20 have been moved to the limit of their upward movement since their heads engage the bottom of the rib 13. The cutter bar 21 is moved upwardly by the spring-pressed pins 23 in all positions of the blade-flexing member and is maintained at all times in shearing contact with the lower face of the blade 15, that is, the pressure of the spring pins 23 is adequate to keep the cutter in constant contact with the flexed blade but not to cause any appreciable change of shape in the blade.

In the modification shown in Figs. 5 and 6 the blade-flexing member 30 is similar to that already described except that it is provided in the upper edge of its side walls with a series

of projecting guard teeth 31, rectangular in cross-section and upwardly tapering as shown in Fig. 6. Each tooth is provided with a transverse outwardly flaring passage 32 so that hairs may pass freely through the teeth and enter the apertures of the blade. The flexible blade 30 in this instance is provided with transverse slots 34 which terminate in enlarged rectangular openings 35 of such dimensions as freely to receive the teeth 31 of the blade flexing member. Accordingly when the blade flexing member 30 is elevated the teeth 31 make interlocking engagement with the blade 33 so that the blade is simultaneously flexed transversely and locked positively against longitudinal movement in the head 12. As already intimated the passages 32 are aligned with the slots 34 of the blade which provide the stationary shearing teeth of the implement. The cutter, supplying the movable shearing teeth, is reciprocated in yielding contact with the under face of the flexed blade 33 in the manner already explained.

In Figs. 10, 11, 13 and 14 is illustrated an implement having certain features of the present invention embodied therein and in which the movable cutter itself acts as a blade-flexing member. The handle 40 is provided with a socket in its upper end for the reception of the head of the implement and with a clamping screw 41 for retaining it in place. The head of the implement comprises a sheet metal shell and solid steel body portion. The shell comprises two upstanding perforated end plates 42 bent up from opposite ends of a bottom plate 43 and spaced apart to receive the solid body portion of the head. The upper portion 44 of the head is provided with a large open recess bounded by spaced side walls which are provided with opposed grooves to receive a flat flexible blade 46. The lower portion 45 of the head is reduced in width and comprises a wide downwardly extending rib of such dimensions as to fit into the socket of the handle 40 above the bottom plate 43 and in position to be engaged by the clamping screw 41. As already explained the end plates 42 extend upwardly at opposite ends of the head and when the head is in place they engage the ends of the blade 46 and prevent it from being displaced longitudinally in the implement.

The flexible blade 46 is shown as provided with a series of transverse slots 47. These slots provide shearing edges in the blade. The individual slots are provided alternately at their opposite ends with rounded enlargements which in use act to collect the hairs to be sheared and to direct them to the shearing zone of the implement. It will be understood that when the head of the implement is removed from the handle 40 and from between the upstanding end plates 42, the blade 46 may be slipped edgewise into the grooves in the side walls of the head, spanning the open recess therein as suggested in Fig. 10.

The upper portion 44 of the head is provided with a longitudinal internal channel opening into the space between its side walls and adapted to receive the vibrating cutter 50. This comprises a flat and elongated bar having shearing teeth 51 in its upper edge and arranged to be supported in shearing engagement with the blade 46 by a pair of spaced swinging struts or links 52. These struts have rounded lower ends which are retained in sockets in the flange portion of the head and are received at their upper ends in flaring openings or recesses in the bottom of the cutter. The cutter 50 is also provided in its

lower face with a recess in which is located an eccentric pin formed on the upper end of the driving shaft 53.

The length of the struts 52 is such that when they occupy an upright or vertical position as shown in Fig. 11 the cutter 50 is forced upwardly into blade-flexing position and the blade 46 is thus maintained in transversely bowed condition. The action of the eccentric pin is to reciprocate the cutter 50 in a short path of longitudinal movement but the amplitude of this movement is not sufficient to produce noticeable vertical movement in the cutter and so the latter is maintained continuous in yielding shearing engagement with the inner face of the flexible blade 46. When the clamping screw 41 is released and the head removed from the handle, the struts 52 may be rocked, as indicated in Fig. 14, sufficiently to lower the cutter 50 from its flexing engagement with the blade 46 and when so released the blade may be removed endwise from between the grooves of the head as already explained.

In Figs. 15, 16 and 17 is illustrated an implement of modified construction in which certain features of the present invention are embodied and in which the blade-flexing member is laterally movable, instead of being movable in a path at right angles to the flexible blade as in implements previously disclosed. In these figures the head only of the implement is shown and this may be used with the handle shown in Figs. 1 and 2 or with the handle shown in Figs. 10 and 11.

The head 54 comprises an upper portion having an open longitudinal recess in its upper face and a shouldered rib of reduced width in its lower portion. One side of the head is made removable and this part 55 comprises the blade-flexing member of the implement and has a longitudinal rib in its inner face arranged to fit a corresponding channel in the side of the head. A clamping screw 56 is provided which is threaded into the body of the head. The integral side of the head 54 and the removable flexing member 55 are both provided with inwardly directed ribs at their upper edges forming longitudinal channels for the reception of a flexible apertured blade 57 shown more particularly in Fig. 9. The open space in the top of the head is bounded by longitudinal shoulders upon which the blade may be preliminarily flexed in bringing the blade-flexing member 55 into its operative relation, that is, one edge of the blade 57 is hooked into the groove in the internal side of the head, then the other edge of the blade is hooked under the rib of the flexing member 55 and the latter is forced into place and drawn inwardly by the clamping screw 56 while the blade 57 is bowed transversely and held in this position as shown in Fig. 18.

The head is provided with a longitudinal channel of rectangular cross-section which opens at its upper edge into the open space in the head and is provided with a pair of spring-pressed balls 58 which normally project slightly above its bottom wall. The cutter itself, which comprises an elongated bar serrated in its upper edge to form shearing teeth, is mounted for reciprocation in the channel in the head and may be reciprocated by operating connection with the motor as already suggested. The blade-flexing member 55 may be adjusted to the limit of its inward movement, as shown in Fig. 16 thus imparting a maximum curvature to the blade 57,

or it may be moved to an intermediate position corresponding to less curvature in the blade.

The blade 57 is formed of thin sheet steel as already explained and is herein shown as provided with two spaced series of rectangular apertures 58 forming stationary shearing teeth. The marginal edges of the blade are roughened or serrated in zones 59 and the overhanging ribs of the blade clamping elements may be correspondingly roughed or corrugated so that longitudinal shifting of the blade is positively prevented when the blade is once clamped in the head.

An alternative form of blade is shown in Fig. 12. This is provided with two series of keyhole slots 63 spaced from each other and outwardly directed in the body and having an intermediate row of circular apertures 64. All of these apertures form shearing edges with which cooperate the movable shearing teeth of the cutter member. The cutter is of such a width as to leave the outer ends of the apertures free to receive hairs as the implement is moved across the face of the user.

Having thus disclosed my invention and described several desirable embodiments thereof for purposes of illustration but not in any limiting sense, I claim as new and desire to secure by Letters Patent:

1. A shaving implement comprising a holder, having side members for engaging the longitudinal edges of a blade, a thin flexible blade having an opening presenting shearing edges, a blade flexing member adjustable with respect to said side members to bow the blade transversely, to varying degrees of curvature, and a reciprocatory cutter yieldingly maintained in contact with the bowed blade.

2. A shaving implement having a flexible apertured blade, a holder having opposed transverse channels for receiving the opposite edges of the blade, adjustable means having a face for engaging the blade between said channels to bow it in its holder, and a reciprocatory cutter distinct from said means for bowing the blade and movable in contact with the bowed blade in a path determined by the curvature which has been imparted to said blade.

3. A shaving implement having a flexible apertured blade, a holder arranged to engage the longitudinal edges of the blade and leave free an intermediate zone therein, a blade flexing member having spaced walls for engaging the blade in said intermediate zone to flex the same, and a cutter arranged to reciprocate between said walls in contact with the flexed blade.

4. A shaving implement comprising a head having a flexible blade held at its edges therein, a blade-flexing member movable in the head to engage an intermediate portion of the blade, adjusting means for said member acting to hold the same against longitudinal displacement in the head, and a movable cutter cooperating with the flexed blade.

5. A shaving implement comprising a head having a flexible blade held at its edges therein, a blade-flexing member shaped to contact with the blade throughout its length, an adjusting screw in the head engaging said member at each end, a reciprocatory cutter positioned by said blade-flexing member in shearing relation to the flexed blade, and a spring device located adjacent to each adjusting screw for holding the cutter against the flexed blade.

6. A shaving implement comprising a holder,

an apertured flexible blade engaged at its edges thereby, adjustable means having a blade-engaging face and being movable for transversely flexing the blade into different positions of transverse curvature, a cutter movable in contact with the blade, and yielding means for holding the cutter against the blade in all positions imparted to the blade by said blade-flexing means.

7. A shaving implement comprising a holder, a flexible slotted blade engaged at its edges by the holder, an elongated blade-flexing member of U-shaped cross section adjustably mounted in the head and having its side walls slotted to provide hair-passages registering with the slots of the blade, and an elongated cutter mounted between the walls of said member to reciprocate in contact with the blade.

8. A shaving implement comprising a holder, a flexible apertured blade, adjustable and normally stationary means having a blade-engaging face for transversely bowing said blade, and a movable cutter having a shearing blade-engaging face maintained in shearing engagement with the bowed blade and movable in a path determined by the curvature that has been imparted to the blade by said blade-bowing means.

9. A shaving implement comprising a holder, a flexible apertured blade removably retained therein, an elongated blade-flexing member having a blade-engaging face and being movable toward and from the blade to flex it transversely, said member being held against longitudinal movement, and a cutter arranged to be reciprocated longitudinally in shearing engagement with the flexed blade and in a path determined by the transverse curvature that has been imparted thereto by said blade-flexing member.

10. A shaving implement comprising a flexible blade having a roughened marginal edge, a holder having roughened means for engaging the blade edge while the latter is curved transversely for preventing longitudinal displacement of the blade, and a reciprocatory cutter.

11. A shaving implement having a head with spaced side walls provided with grooves and bounding an open recess in the head, a flexible blade held at its edges in said grooves and spanning the recess, and a blade-flexing member having a blade-engaging portion and being movable in the recess to engage the blade and impart transverse curvature thereto and a reciprocatory cutter movable adjacent to said blade-flexing member and in contact with the flexible blade.

12. A shaving implement having a head with spaced-blade-engaging walls, a channelled blade-flexing member movable in the space between said walls to flex a blade held thereby, a cutter carried by the blade-flexing member, means for vibrating the cutter, and independent means for lifting the cutter in its carrier toward the flexed blade.

13. A shaving implement comprising a holder, having spaced members for engaging the longitudinal edges of a blade, a thin flexible blade having transverse slots presenting transverse shearing edges, a blade-flexing member having a blade-engaging face and being movable in the holder to flex transversely a blade in the holder, and a reciprocatory cutter having a face with transverse shearing edges maintained in contact with the flexed blade, without appreciably changing the shape of the flexed blade from that determined by said blade-flexing member.

NICHOLAS TESTI.
